PERFORATING APPARATUS

Norbert K. Engst, La Grange, Ill., assignor to
 Western Electric Company, Incorporated, New
 York, N. Y., a corporation of New York

Application November 1, 1934, Serial No. 750,919

16 Claims. (Cl. 164—113)

This invention relates to perforating apparatus, and more particularly to apparatus for punching statistical cards.

It is an object of the present invention to provide a simple, inexpensive perforating mechanism which is flexibly operated.

In accordance with one embodiment there is provided a coordinate arrangement of punch actuators and punch selectors positioned above a plurality of punches arranged in columns and transverse rows. A selector is provided for each column of punches and an actuator is provided for each row of punches. A ten key keyboard controls the operation of the actuators and is connected through a distributor switch and a switchboard to select and operate the punch selectors in any desired order as controlled by the switchboard.

A complete understanding of the invention may be had by reference to the following detailed description thereof when considered in conjunction with the accompanying drawings, wherein

Fig. 1 is a plan view of a mechanism embodying the features of applicant's invention;

Fig. 2 is a circuit schematically showing the electrical connections between the various parts of the apparatus;

Fig. 3 is a vertical sectional view along the line 3—3 of Fig. 1 in the direction of the arrows, and

Fig. 4 is a vertical sectional view taken along the lines 4—4 of Fig. 1 in the direction of the arrows.

Referring now to the drawings wherein like reference numerals designate the same parts throughout the several views, particular reference being made to Fig. 1, the numeral 5 designates a base upon which the mechanism is supported. In the lower right hand corner of the base 5 there is provided a keyboard 6 on which there are mounted ten keys 7 corresponding to the digits 1 to 9 and 0. These may be any suitable type of non-locking electrical switching keys and may be mounted in any suitable manner upon the base 5.

Referring now to Fig. 3, it will be seen that there is mounted upon the base 5 a die plate 8 and that the base 5 is cut out as shown at 9 to permit scrap forced through the die plate 8 to fall into a suitable receptacle (not shown). Mounted directly above the die plate 8 is a guide 10 in which are positioned four hundred and fifty headed perforating pins 11, which are in direct vertical alignment with four hundred and fifty holes 12 in the die plate 8. Guide 10 is cut away at its bottom surface as shown at 13 to receive a card 14.

The perforating pins 11 are arranged in columns of ten to a column and transverse rows of forty-five to a row, a stripper plate 20 being provided for each row of perforating pins. The stripper plates 20 are normally urged upwardly 5 (Figs. 3 and 4) by springs 21 positioned in the upper portion of the guide member 10 for returning the perforating pins to their normal position, after they have been depressed in a manner to be described later.

Extending longitudinally of each column of perforating pins 11 is a selector strip 22 formed of a thin flexible sheet of metal and having secured to the underside thereof (Figs. 3 and 4) ten projections 23 so positioned that when the strip 22 is 15 in its normal inoperative position the projections are in vertical alignment with the spaces between the heads of the perforating pins 11. At the left end (Fig. 3) of each of the selector strips 22, there is secured an inverted L shaped stop member 25 20 which serves to position accurately the strip when it is operated. A spring 24 having one end set into the guide 10, has its other end engaging the downwardly extending portion of the L shaped member 25 to normally hold the selector strips 25 in their left hand position (Fig. 3). A stop member 26 is fixed to the bottom surface of each selector strip 22 and when the spring 24 moves the selector strip to the left the stop member will engage the guide member 10 to position accurately 30 the selector strip in its inoperative position. The right end of each of the selector strips 22 is secured to an actuating bar 30 positioned between suitable guides 31 and having adjacent its right hand end an aperture 32 adapted to receive the vertically 35 extending arm of a bell crank lever 33. There is provided one bell crank lever 33 for each actuating bar 30, and all of the bell crank levers are pivoted upon a rod 34 mounted in side plates 35. The bell crank levers 33 are normally urged about the rod 40 34 in a clockwise direction (Fig. 3) by contractile springs 36 individual to each bell crank lever. There are provided three arms on each of the bell crank levers, one extending into the aperture 32 of the selector strip 22, one connected to the contractile springs 36, and one extending upwardly as shown at 37. The upwardly extending arm is urged by the contractile springs 36 into engagement with the armature 38 of an electromagnet 39. The armatures 38 are pivoted at 42 and the electromagnets are supported on plates 43 extending between the side plates 35.

In order to mount the electromagnets 39 so that they will have their armatures extending into the respective vertical planes of the holes 55

of the record card positioned on the die plate, thereby to have direct control of the selector strips 22, the electromagnets 39 have been arranged in an arcuate staggered relation as shown 5 in Figs. 1 and 3. A cover 40 is provided for enclosing the magnets 39.

Extending longitudinally of each row of perforating pins 11 is an actuator bar 50 having associated therewith a pair of solenoids 51, the 10 movable cores 52 of which are secured to the actuator bar 50 so that upon energization of the solenoids 51 the associated actuator bar will be moved downwardly against the energy stored in springs 53. A portion 54 (Figs. 3 and 4) of the 15 guide 10 restrains the movement of the actuator bars 50 upwardly beyond a predetermined position.

As disclosed in Fig. 2 each of the keys 7 is equipped with three contacts 58, 59 and 60. Contacts 58 are connected to ground at 61 and upon 20 operation of any key 7 ground will be connected from 61 through the contacts 58 successively to the contacts 59 and 60 of the key operated. All of the contacts 59 are connected to a rotatable brush 25 62 of a selector switch designated generally by the numeral 63 and the contacts 60 are connected individually to the electromagnets 51 which are connected to grounded battery at 56.

The selector switch 63 is of the type used in 30 automatic telephone systems and comprises the brush 62, and a plurality of contacts 64, of which there are in the particular embodiment disclosed herein forty-five arranged arcuately and adapted to be engaged by the brush 62 to control the 35 forty-five columns of punches associated with the forty-five columns on the usual type of statistical card.

The contacts 59 are also connected through the winding of an electromagnet 65, forming a 40 part of the selector switch 63, to grounded battery at 55. Upon energization of the electromagnet 65 it will attract its armature 66, which is normally urged in a counterclockwise direction about a pivot 67 by a spring 68. The armature 66 has a pawl 69 pivotally connected thereto, which upon energization of the electromagnet 65, will be moved to the right (Fig. 2) over a ratchet wheel 70 and upon release of the electromagnet 45 65, the spring 68 will move the ratchet wheel to 50 drive the brush 62 forward into engagement with its next associated contact 64.

Each of the contacts 64 of the selector switch 63 is connected to one terminal of a jack 71 in a small switchboard indicated at 72 (Figs. 1 and 55 2). There are provided forty-five plugs 73 which may be inserted in the jacks 71 of which there are forty-five. The plugs 73 are connected to the electromagnets 39, and when the plugs 73 are inserted in the jacks 71 circuits may be set up 60 whereby operation of various keys 7 in the keyboard 6 may control successively any selected ones of the electromagnets 39, depending upon the method in which the jacks 71 and plugs 73 are cross-connected. Each jack 71 has a break contact 78 which is broken upon the insertion of a plug 73 in the jack. When a plug 73 is inserted in the jack 71, contact 78 will be broken and the contact 64 associated with that jack will be connected through the plug 73 to its associated electromagnet 39, which is connected to grounded 65 battery at 80. When no plug is inserted in a jack 71, the contact 78 will provide a path from grounded battery 55 through electromagnet 65 to ground at 79, through the armature of electromagnet 65 in normal position, to cause the brush

62 to step until it engages a contact 64 associated with a jack 71 in which a plug 73 has been inserted.

The contacts 60 associated with each of the keys 7 are connected to the solenoids 51 for the digits 1 to 9 and 0, respectively, so that immediately after a selector strip 22 has been actuated the continued movement of the key 7 will close a circuit to energize the solenoids 51 associated with that key.

The operation of a selector strip 22 under control of a key will move the projections 23 of the operated selector strip out of normal position to a position where they are in direct vertical alignment with the heads of their associated perforating pins 11 just prior to the operation of the selected solenoids 51. When a pair of solenoids 51 are operated, a selector strip having been operated, the perforating pin 11 at the junction of the actuated actuator bar 50 and selector strip 22 will be forced through the card 14. The operation of the solenoids 51 is delayed until after the operation of the magnet 39, partly by reason of their greater inertia and partly because their contact 60 is closed subsequently to the closing of contact 59. If desired the solenoids 51 may be made additionally slow acting by well known expedients.

An additional key (not shown) may be provided for spacing over columns of the card in which it is not desired to perforate any information. This key would be similar to the keys associated with the digits except that it would have no contact leading to the solenoid 51 and in its operation will simply advance the distributor brush 62 step-by-step over contacts 64 associated with unused columns on the statistical card. This key has not been shown since the construction of the embodiment disclosed herein is such that if the plugs 73 associated with any of the forty-five electromagnets 39 are inserted in certain successive ones of the jacks 71, the selector switch 63 will automatically step its brush 62 over all of the contacts 64 which are not connected, by the insertion of plugs, to electromagnets 39. This key is useful when it is desired to set the machine for certain types of punching operations in which predetermined ones of the columns of the record cards are to be punched in the majority of cases, but in some few selected cases predetermined ones of the columns are to be left blank. In such event the key may be utilized for advancing the brush 62 over contacts connected to magnets 39 which are not to be used without changing the setting of the machine.

It is believed that a brief description of the operation of the machine will aid in the understanding of the invention, and therefore let it be assumed that the switchboard 72 has been set by inserting the plugs 73 associated with the 1st, 2nd, 3rd, 4th, and 42nd, 43rd, 44th and 45th electromagnets 39 in the first eight jacks associated with the contacts 64 of switch 63, and that it is desired to leave blank on the record card the 9th to 45th columns. It would then be necessary to operate the keys 7 eight times, and the brush 62 would be returned to the position shown in Fig. 2. Upon operation of any digit key, for example, key 7 for the digit 5, a circuit will first be completed from grounded battery 55 through the electromagnet 65, the closed contacts of the key to ground at 61, to energize the electromagnet 65 to move the pawl 69 to the right against the tension of spring 68. Simultaneously with the operation of electromagnet 65, a circuit will be completed

from grounded battery at 80 through one of the electromagnets 39, the plug 73, jack 11, contact 64, and the brush 62 to ground at 61. This will result in the operation of one of the electromagnets 39, causing it to pull its associated selector strip 22 to the right (Fig. 3) to bring the projections 23 over the heads of the perforating pins 11 in the selected column. Immediately after the contact is made between contacts 58 and 59, contact will be made between the contact 59 and 60 associated with the digit 5 key, and that will complete the circuit from grounded battery at 56 to the solenoids 51 associated with the digit 5 to ground at 61, thereby causing the actuator bar 50 to be moved downwardly and since one of the selector strips 22 has been moved to the right (Fig. 3) the actuator bar in moving downwardly will drive the perforator pin 11 selected by the coordinate action of the actuator bar and the selector strip 20 through the card 14. As soon as the key 1 associated with the digit 5 is released, electromagnet 65 will fall back and spring 68 will cause the pawl 69 to advance the distributor brush 62 into engagement with the next contact, whereupon the 25 operation may be repeated for any selected keys, the distributor brush advancing in a similar manner until the information desired to be punched in the card has been perforated therein.

As soon as the distributor brush 62 reaches a contact 64 which is associated with a jack 11 in which no plug 73 has been inserted, the brush 62 will automatically step over the contacts 64 until it reaches a contact associated with a jack in which a plug 73 has been inserted, due to the 30 completion of a circuit from ground at 79 through the armature 66, break contact 78, contact 64, brush 62, electromagnet 65 to grounded battery at 55. This operation in the example given will set the punch for the next card and since the 35 stepping over unused contacts is rapid, the machine will be ready for a new card as soon as the punched card is removed.

Obviously the switchboard may be cross-connected in any manner and information set up on the keys may be punched in any desired column of the card by making suitable cross-connections in the switchboard 72 and if it were desired to use the combinational hole system of punching, which is well known in tabulating practice, the 40 circuit connections running from the keys to the solenoids 51 might be suitably arranged.

Although a specific embodiment of the invention has been desired in detail herein, it is to be understood that applicant is not limited to the 45 specific disclosure but the scope of the invention is to be limited only by the appended claims, for example, the invention is not limited to the type of punch in which the perforating is done at the time the pins are depressed but the pins 50 might be locked down and the cards punched later.

What is claimed is:

1. A perforating mechanism comprising a plurality of perforators arranged in columns, and a 55 plurality of elements positioned at angles to each other, and jointly operable for selecting and operating any perforating element in any column.

2. A perforating mechanism comprising a plurality of transversely positioned elements, a 60 plurality of perforating members associated therewith, and means for selecting any two transversely positioned elements to actuate one of the 65 perforators.

3. A perforating mechanism comprising a 70 plurality of perforators arranged in columns, means

for actuating a perforator comprising a selector positioned over each column, a plurality of actuators extending over all columns, and means for selecting in one operation an actuator and a selector to cause the actuation of a perforator.

4. A perforating apparatus comprising a plurality of perforating members arranged in columns and transverse rows, a selector positioned over each column, an actuator positioned over each row, means for selecting and actuating any 10 selector and actuator to operate the perforating member associated with the selected selector and actuator.

5. A perforating mechanism comprising a plurality of perforating elements, a plurality of coordinate elements, and means for jointly operating the coordinate elements to select and actuate any of the perforating elements.

6. In a perforating mechanism, a plurality of 20 perforating members, a group of elements arranged as ordinates, a group of elements arranged as abscissae to form a coordinate system, and means for actuating said elements to select and actuate any perforating member.

7. In a perforating apparatus, a group of elements arranged as ordinates, a group of elements arranged as abscissae to form a coordinate system, a perforating member at each coordinate point of said system, and means for selecting and actuating said elements to actuate the perforating members.

8. In a perforating apparatus, a ten key keyboard, a plurality of perforating members positioned at coordinate points in a coordinate system, a plurality of actuator bars arranged as abscissae, a plurality of selector elements arranged as ordinates, a pair of solenoids individual to and controlled by each key for actuating the actuator bar associated with each key, an electromagnet 35 associated with each selector element for actuating it, a distributor switch comprising a brush associated with all the keys, and a plurality of contacts associated with said brush and equal in number to said electromagnets, and a switchboard 40 for connecting said contacts to any of said electromagnets.

9. In a perforating apparatus, a keyboard having keys representing characters, a plurality of perforating members arranged in columns and rows, actuator bars representing characters and 50 associated with rows of perforating members, a distributor switch controlled by said keys, a selector element associated with each column of perforating members, actuating means for the selector elements, and a switchboard interposed 55 between said distributor switch and said actuating means for controlling the order in which the selector elements will be operated.

10. In a perforating apparatus, a keyboard having keys representing characters, a plurality of 60 perforating members arranged in columns and rows, actuator bars representing characters and associated with rows of perforating members, a distributor switch controlled by said keys, a selector element associated with each column of 65 perforating members, actuating means for the selector elements, a switchboard interposed between said distributor switch and said actuating means for controlling the order in which the selector elements will be operated, and means 70 for returning the distributor switch to normal position.

11. In a perforating apparatus, a keyboard having keys representing characters, a plurality of 75 perforating members arranged in columns and

- rows, actuator bars representing characters and associated with rows of perforating members, a distributor switch controlled by said keys, a selector element associated with each column of perforating members, actuating means for the selector elements, a switchboard interposed between said distributor switch and said actuating means for controlling the order in which the selector elements will be operated, and means under control of the switchboard for actuating the distributor switch automatically when it is desired not to operate predetermined selector elements.
12. A perforating mechanism for tabulating cards comprising a plurality of perforating pins arranged in columns, a plurality of selectors one positioned over each column, a plurality of actuators positioned transversely of the selectors, a keyboard for determining the order in which the actuators will be operated, and means including a distributor switch, a switchboard and the keys for determining the order in which the selectors will be operated.
13. A perforating mechanism for tabulating cards comprising a plurality of perforating pins arranged in columns, a plurality of selectors one positioned over each column, a plurality of actuators positioned transversely of the selectors, a keyboard for determining the order in which the actuators will be operated, and means for de-
- termining the order in which the selectors will be operated.
14. In a perforating apparatus, a plurality of perforating members arranged in columns, a plurality of selector elements associated with said perforators, a plurality of actuators associated with said perforators, and means for controlling the joint action of the selectors and actuators to operate the perforators in any desired order.
15. A perforating mechanism for tabulating cards comprising a plurality of perforating pins arranged in columns and transverse rows, a keyboard having keys corresponding to said rows, an actuator for the pins of each row and controlled by the respective key, and means for conditioning the pins of one column at a time for actuation by said actuators.
16. A perforating mechanism for tabulating cards comprising a plurality of perforating pins arranged in columns and transverse rows, a keyboard having keys corresponding to said rows, an actuator for the pins of each row and controlled by the respective key, and means for conditioning the pins of one column at a time for actuation by said actuators, said conditioning means being controlled by said keys so as to condition different columns of pins for successive operations of the keys respectively.

NORBERT K. ENGST. 36
